DESIGN FOR A HANDLE

William Van Prooyen, East Grand Rapids, Mich.,
assignor to Forbes Stamp Company, Grand Rapids, Mich., a corporation of Michigan

Application August 21, 1944, Serial No. 114,961

Term of patent 3½ years

(Cl. D10—8)

To all whom it may concern:

Be it known that I, William Van Prooyen, a citizen of the United States, residing at East Grand Rapids, in the county of Kent and State of Michigan, have invented a new, original, and ornamental Design for a Handle, of which the following is a specification, reference being had to the accompanying drawing, forming part thereof.

Fig. 1 is a perspective view of a handle showing my new design.

Fig. 2 is a plan view of the same.

Fig. 3 is a side view of the same, and

Fig. 4 is an end view of the same.

I claim:

The ornamental design for a handle, substantially as shown.

WILLIAM VAN PROOYEN.
